(57) **CLAIM**

The ornamental design for an automobile front end, as shown and described.

DESCRIPTION

FIG. 1 is a front perspective view of an automobile having the automobile front end showing our new design;

FIG. 2 is a side elevational view thereof;

FIG. 3 is an opposite side elevational view thereof; and,

FIG. 4 is a front elevational view thereof.

It will be understood that the broken lines shown in the drawings illustrate portions of the automobile front end that form no part of claimed design.
